UNITED STATES PATENT OFFICE.

RALPH T. GUYER, OF ELKHART, INDIANA.

ENGINE VALVE MECHANISM.

1,170,249.

Specification of Letters Patent.

Patented Feb. 1, 1916.

Application filed May 10, 1915. Serial No. 26,987.

To all whom it may concern:

Be it known that I, RALPH T. GUYER, a citizen of the United States, residing at Elkhart, in the county of Elkhart and State of Indiana, have invented new and useful Improvements in Engine Valve Mechanism; and I do hereby declare the following to be a full and exact description of the invention, such as will enable others skilled in the art to which it appertains to make and use the same.

My invention relates to internal combustion engines and especially to engines of the four cycle type.

15 The objects of my invention are as follows: first, the production of an explosion engine having a novel and efficient form of rotary valve; second, the production of an engine having a rotary valve; and third, 20 means for lubricating the same, and third, novel and efficient means for relieving the valve of the force of the explosion.

Further objects will appear and be described in the specification following.

25 In the accompanying drawings, Figure 1 is a section in elevation through the top of an engine cylinder embodying the invention; Fig. 2 is a section on the line 2—2 of Fig. 1; Fig. 3 is a plan view of the valve top; Fig. 4 is a view in elevation of the preferred form of the rotary valve; and Fig. 5 is a plan view of the valve seat on the cylinder head.

30 Similar numerals refer to similar parts and members throughout the several views on the drawings.

Numeral 1 designates the top of an explosion engine cylinder bored at 2 to receive a piston 3 for reciprocation therein. 40 The cylinder 1 is provided with a water jacket 4 open at its top to communicate with the water jacket of the cylinder head hereinafter described.

Numeral 5 designates a cylinder head rigidly secured to the cylinder top in any suitable manner, and closing same. The head 5 is provided with a water jacket 6, in communication with the cylinder jacket 4, and a water outlet opening 7.

50 The numeral 8 designates a conical valve seat formed on the surface of the cylinder head 5, and numerals 9 and 10 designate, respectively, exhaust and fuel intake ports, or openings, formed in the head 5, in communication with the atmosphere, and terminating at their inner ends in the exhaust

and fuel inlet ports 9' and 10', respectively, in the surface of the valve seat 8. The exhaust and intake ports 9 and 10 are placed, for most purposes and uses, at an interval 60 of about ninety degrees relation to each other, but for special purposes this angle may be varied and made greater or less, according to the purpose to be accomplished.

The numeral 11 designates an annular 65 conically formed valve rotatively seated upon the valve seat 8 of the head 5, and carried by the valve stem 12 upon which it is rigidly mounted. Valve stem 12 is provided with an annular section 13 journaled 70 for rotation within the bore 14 formed in the cylinder head 5, and is also provided with a squared portion 15 which is arranged within the squared hole 16 of the gear wheel 17 with enough play to permit of longitudinal movement of the gear 17 upon the valve stem at 15.

The numeral 18 designates a gear wheel meshing with the gear 17 and provided with one half the number of teeth carried by the 80 gear 17, mounted upon a shaft 19 and rigidly secured thereto. The shaft 19 is driven by and at equal speed with the engine crank shaft, such driving means not being shown.

The numeral 20 designates a coil spring 85 seated with a thrust upon the hub of the gear wheel 17 and held in position around the valve stem 12 by a spring washer 21 and a pin 22. The spring 20 holds the valve 11 securely upon its seat 8 at all times, yet 90 permitting rotation freely, and exerts sufficient tension to withstand the vacuum created in the cylinder when the piston 3 is descending on its suction stroke, or movement.

95 The numeral 23 designates a spark plug opening formed in the head 5 at a point substantially opposite the port 10, and adapted to be closed by a spark plug of any suitable design.

The numeral 24 designates a valve port, of substantially truncated sector formation, formed in the valve 11 and extending from a point intermediate its center and periphery to the outer periphery thereof to obtain 100 all possible port area. The port 24 is adapted to alternately register with exhaust and intake ports 9' and 10' for exhaust and fuel intake purposes, respectively, and during the compression and working movements of the piston 3 is necessarily, and designed and timed to be, out of registry or

communication, with both of said ports which are closed and sealed during said cycles.

The numeral 25 designates a squared section of the valve stem 12 arranged within a squared opening 26 in the center of the valve 11 to prevent rotation of the valve 11 on the stem 12, the extension of section 25 being annular and screw threaded to carry 10 a nut 27 for tightly forcing the valve 11 against the annular shoulder 13 of the stem section 13. At Fig. 4 I show the preferred form of valve and stem which are integral and made of any suitable metal, and provided with the journal section 13 and the 15 squared section 15 for receiving gear wheel 17 and having the same functions as the correspondingly numbered parts of the detachable valve stem 12 shown in Fig. 1.

20 The numeral 28 designates an oil, or lubricant, chamber formed in the cylinder head 5 and within which the lower end of valve stem section 13 rotates, and into which the conical center of the valve 11 slightly projects.

25 The numeral 29 designates a lubricant supply pipe placing the oil chamber interior in communication with the exterior of the head 5, through which lubricant may be introduced to the chamber 28 by gravity or pump in any suitable manner.

30 Numeral 30 designates an annular oil groove formed in the upper, or seating, surface of the valve 11 adjacent its center 35 but below the outer periphery of the oil chamber 28 and between it and the outer periphery of the valve 11. And numerals 31 designate tangential oil grooves extending radially from the groove 30 toward the 40 outer periphery of the valve 11 but ceasing at points between said outer periphery and said groove to retain the lubricant as long as possible.

45 At Fig. 5 I show a plan view of the valve seat 8 and the ports 9' and 10' opening thereto. Thereon, the numerals 32 designate a plurality of radial grooves formed in the valve seat surface and extending centrally from the outer periphery thereof, 50 which is of greater diameter than the diameter of the valve 11, to points in a circle concentric with oil groove 30 but of greater diameter. I provide the grooves 32 not only to reduce the natural frictional resistance between the valve 11 and its seat 8, 55 but also to permit the compression of the explosion to enter therein to partially relieve the valve and actuating mechanism of the pressure thereof, thereby obtaining pressure on both sides of the valve 11. It is understood that the ignition points of the 60 spark plug located in the opening 23 are in communication with the cylinder bore 2 when a charge is compressed therein and 65 ready for ignition, and also that the valve

11 is rotated in the direction indicated by the arrows in Figs. 2 and 3 to obtain the valve port registration with the exhaust and inlet ports 9 and 10 at the proper times and for the purposes mentioned and understood. 70

I claim:

1. In an internal combustion engine, the combination of an engine cylinder provided with a head, said head being provided with a valve seat having a centrally formed lubricant recess therein; means for supplying lubricant to said recess; and a valve rotatively mounted upon said valve seat, covering said lubricant recess and forming the lower wall thereof. 75

2. In an internal combustion engine, the combination of an engine cylinder provided with a head, said head being provided with a conical valve seat having a centrally formed lubricant recess therein; means for supplying lubricant to said recess; and a conically faced valve rotatively mounted upon said valve seat, covering said lubricant recess and forming the lower wall 85 thereof. 90

3. The combination of an engine cylinder provided with a cylinder head, said head being provided with a valve seat and grooves formed in said valve seat; and a valve rotatively mounted upon said valve seat, said grooves extending radially to a point in the valve seat which is beyond the valve circumference and adapted to reduce frictional resistance between the valve and 95 its seat. 100

4. The combination of an engine cylinder provided with a cylinder head, said head being provided with a conical valve seat and grooves formed in said valve seat; and a conical valve rotatively mounted upon 105 said valve seat, said grooves extending radially to a point in the valve seat which is beyond the valve circumference and adapted to reduce frictional resistance between the valve and 110 its seat. 115

5. In an explosion engine, the combination of an engine cylinder provided with a cylinder head, said head being provided with a valve seat upon the surface of which a plurality of grooves are formed, said grooves being in communication with the cylinder interior and adapted to receive the compression of the explosion in the cylinder; a valve rotatively mounted upon said valve seat; ignition means; and means for rotating said valve. 120

6. In an explosion engine, the combination of an engine cylinder provided with a cylinder head, said head being provided with a conical valve seat upon the surface of which a plurality of grooves are formed, said grooves being in communication with the cylinder interior and adapted to receive the compression of the explosion in the cylinder; ignition means; and means for rotating said valve. 125 130

inder; a conical valve rotatively mounted upon said valve seat; ignition means; and means for rotating said valve.

7. In an explosion engine, the combination of an engine cylinder provided with a cylinder head, said head being provided with a conical valve seat; a conical valve rotatively mounted upon said valve seat; ignition means; means provided on the

valve seat for conducting the cylinder explosion compression to the seat contacting surface of the valve; and means for rotating the valve.

In witness whereof I have hereunto affixed my signature this 6th day of May, 15
A. D. 1915.

RALPH T. GUYER.
